poration of New York

Application July 6, 1944, Serial No. 114,323

Term of patent 14 years

(Cl. D80—11)

To all whom it may concern:

Be it known that I, William John Bovers, a citizen of the United States, residing at Caldwell, in the county of Essex and State of New Jersey, have invented a new, original, and ornamental Design for a Combination Showcase and Merchandise Display Trays, of which the following is a specification, reference being had to the accompanying drawing, forming part thereof.

Fig. 1 is a perspective view of a combination

showcase and merchandise display trays showing my new design.

Fig. 2 is a top plan view of the combination showcase and merchandise display trays illustrated in Fig. 1.

I claim:

The ornamental design for a combination showcase and merchandise display trays, substantially as shown.

WILLIAM J. BOVERS.
